Patented June 30, 1903.

UNITED STATES PATENT OFFICE.

OTTO LEIGH AND PHILEMON O. DICKINSON, OF NEWARK, NEW JERSEY.

DESIGN FOR A BACK FOR BRUSHES, MIRRORS, OR SIMILAR ARTICLES.

SPECIFICATION forming part of Design No. 36,391, dated June 30, 1903.

Application filed June 5, 1903. Serial No. 160,271. Term of patent 3½ years.

To all whom it may concern:

Be it known that we, OTTO LEIGH and PHILEMON O. DICKINSON, both citizens of the United States, residing at Newark, county of Essex, State of New Jersey, have invented a new, original, and ornamental Design for the Back of a Brush, Mirror, or Similar Article, shown in the accompanying drawing.

What we claim is—

The ornamental design for back of a brush, mirror or similar article, as herein shown.

OTTO LEIGH.

PHILEMON O. DICKINSON.
